ATTORNEYS

UNITED STATES PATENT OFFICE.

ROBERT E. WILLIAMS, OF DALLAS, TEXAS.

BRUSH.

No. 823,312.

Specification of Letters Patent.

Patented June 12, 1906.

Application filed December 1, 1905. Serial No. 289,809.

To all whom it may concern:

Be it known that I, ROBERT E. WILLIAMS, a citizen of the United States, and a resident of Dallas, in the county of Dallas and State of Texas, have invented a new and Improved Brush, of which the following is a full, clear, and exact description.

This invention relates particularly to improvements in bath-brushes, the object being to provide a brush having in its combined construction a plurality of devices for acting variously on a person when the brush is in use.

I will describe a brush embodying my invention and then point out the novel features in the appended claims.

Reference is to be had to the accompanying drawings, forming a part of this specification, in which similar characters of reference indicate corresponding parts in all the figures.

Figure 1 is a bottom plan of a brush embodying my invention with parts broken away to show other parts. Fig. 2 is a top plan thereof. Fig. 3 is a section on the line 3 3 of Fig. 2, and Fig. 4 is a section on the line 4 4 of Fig. 2.

Referring to the drawings, 5 designates the frame or back of the brush, consisting of flexible material—such, for instance, as soft rubber. For the sake of lightness and also to reduce the cost of manufacture this frame or back is made in skeleton form, as clearly indicated in Fig. 2. The rubbing surface of the brush consists of projections 6, consisting of rubber extended from the frame or back and adapted to readily yield when moved over a person's body. On the ends of the frame or back and consisting of yielding rubber are segmented scrapers 7, which, to provide for sufficient rigidity, are somewhat thicker at the base than at the free edges. These scrapers are not only designed to remove wrinkles from a person's face, but are also designed to remove dirt from the body.

At the center of the brush is an opening through which a massage-roller 8 extends. This roller is circumferentially ribbed and consists, preferably, of rubber. It is mounted in a casing 9, of suitable metal, and rotates on a rod 10, extended lengthwise through the casing. The casing is secured at its ends to the side members of the frame or back by means of screws 9^a, as indicated in Fig. 2, which will not only firmly hold the casing in

position, but will prevent lateral spreading of the brush. The casing at the top is provided with perforations 11, through which the prongs of a wire handle may be passed when a rigid handle is desired. The brush is 60 also provided with a hand-strap consisting of two sections 12 13, respectively, connected to opposite sides of the brush frame or back and engaged one with the other at the free ends by means of a button 14.

Extended between the center bars of the frame or back and near the ends are short rods 15, with which the ends of straps or the like may be connected so that the brush may be readily moved over portions of the body 70 that could not be otherwise reached. Embedded in the frame or back, above the rubbing-surface, at each side of the roller are four magnetic plates 16, the plates of a side engaging one against another. These plates 75 are designed to form a compound magnetic battery on each side of the roller.

Having thus described my invention, I claim as new and desire to secure by Letters Patent—

1. A brush comprising a back of yielding material, a rubbing-surface of yielding material connected to the back, and a massage-roller arranged in the brush.

2. A brush comprising a back of yielding 85 material, a rubbing-surface thereon consisting of yielding projections, the said brush having an opening through it, a metal casing arranged over said opening and a ribbed roller mounted to rotate in the casing. 90

3. A brush comprising a back of skeleton form, a flexible rubbing-surface on said back, and rods arranged in said back near the ends, engaging with straps.

4. A brush comprising a back, having an 95 opening through it, a yielding rubbing-surface on the back, a massage-roller arranged in said opening, and a casing extended over the roller and provided with perforations to receive members of a handle.

5. A brush comprising a back of flexible material, a rubbing-surface on the back, consisting of soft-rubber projections, a roller supported in the brush, and a hand-strap attached to the brush-back.

6. A brush comprising a frame of yielding material, a yielding rubbing-surface on said frame, yielding scrapers extended from the frame and a circumferentially-ribbed roller mounted in the brush.

7. A brush comprising a back or frame of
skeleton form, a yielding brush material on
said frame, a hand-strap consisting of two
sections connected to opposite sides of the
frame, and means for detachably securing the
free ends of the sections together.

5 In testimony whereof I have signed my

name to this specification in the presence of
two subscribing witnesses.

ROBERT E. WILLIAMS.
